UNITED STATES PATENT OFFICE.

ERNEST LUNN, OF CHICAGO, ILLINOIS, ASSIGNOR TO THE PULLMAN COMPANY, OF CHICAGO, ILLINOIS, A CORPORATION OF ILLINOIS.

BELT-CLEANING DEVICE.

Application filed August 1, 1924. Serial No. 729,658.

This invention relates to belt cleaning devices, and more particularly to means for removing foreign matter from transmission belts.

5 One of the objects of the invention is the provision of new and improved means for removing ice, snow, etc. from the pulley engaging surface of transmission belts.

Another object of the invention is the provision of new and improved means for removing foreign matter from the pulley engaging surface of transmission belts, that is properly held and automatically operated by contact with the moving belt.

10 Other objects of the invention are the provision of a new and improved belt cleaner that is simple in construction, cheap to manufacture, easily installed, efficient in operation, that is composed of few moving parts, 20 and that is not likely to become broken or get out of order.

Other and further objects and advantages of the invention will appear from the following description taken in connection with 25 the accompanying drawings, in which

Fig. 1 is an end elevation of a generator and drive belt for operating the same adapted to be carried by railway cars, showing my invention in position, with parts broken 30 away and with the generator detached from the car;

Fig. 2 is a plan view of the same with parts in section and parts broken away;

Fig. 3 is a view similar to Fig. 1 showing 35 a modified form of the device;

Fig. 4 is a plan view of the same with parts in section and parts broken away;

Fig. 5 is a plan view of a still further modified form of the device;

40 Fig. 6 is an elevation of the same, with parts broken away and parts in section;

Fig. 7 is a section on line 7—7 of Fig. 8;

Fig. 8 is a section on line 8—8 of Fig. 7;

45 Fig. 9 is an end elevation of a modified form of cleaner device; and

Fig. 10 is a section on line 10—10 of Fig. 9.

On the drawings, the reference character 1 designates any type of driven mechanism 50 which is adapted to be driven by a suitable belt 2 trained over a pulley 3 associated with said mechanism. For simplicity of illustration and convenience in description the mechanism 1 is disclosed as being an electric 55 generator that is adapted to be carried by

railway cars to furnish electricity for lighting purposes, etc. The generator 4 is provided with a supporting arm 5 which is adapted to be pivoted to the underside of the car in the usual manner. Since the generator and the means for mounting the same on the car constitute no part of the present invention the details of the generator are not disclosed, nor is the same shown as being mounted on a railway car. It is understood, 60 however, that these features are of the usual or well known construction.

It is well known that transmission belts that are exposed more or less to the accumulation of foreign matter on the pulley engaging surface will lose a considerable proportion of their efficiency. This is especially true of belts on which snow and the like are likely to accumulate, for the reason that the snow adhering to the belt will be 70 pressed against the same with sufficient force to convert it into a coating of ice on the pulley engaging surface of the belt thereby causing serious slippage of the belt with a corresponding decrease in efficiency of the 75 belt operated mechanism.

Suitable means have been provided for removing foreign matter from the belt during the operation of the mechanism 1. For convenience in mounting, the belt cleaning device may be and preferably is located 80 adjacent to the pulley 3.

Generators for furnishing electricity to railway cars are as a rule operated from one of the car axles by a belt drive and as the generator is usually located beneath the car 90 the belt is likely to have deposited on it, snow, sleet, and the like carried by air currents induced by the rapidly moving belt and train. Especially is this true when the 95 snow is light and powdery. As a result of the pressure of the driving belt against the pulleys on the generator and car axle a thin film of ice is formed on these pulleys which is conducive to the slipping of the belt in 100 driving the generator.

Suitable means for automatically cleaning the belt or for preventing an objectionable accumulation of foreign matter thereon will 105 now be described.

As shown in Figs. 1 and 2 a belt cleaning member 7 which may be and preferably is in the form of a rotating brush, although it may be otherwise, is rotatably mounted in a suitable support 8 pivoted to the arms 9 110

and 10 which are hingedly connected to a bracket 11. The bracket 11 is secured to any suitable support as by being connected to the generator 4.

5 In order to prevent undue wear on the belt by the contacting surface of the brush or cleaner member provision is made for supporting the same in proximity to the pulley engaging face of the belt. Any suitable 10 means may be employed for this purpose. In the form of the device selected to illustrate one embodiment of the invention, the supports 8 are provided with one or more guides 12 that may be in the form of wheels 15 which are adapted to engage the belt 2 for holding the cleaner member 7 at the proper distance therefrom. It is only necessary that the cleaner member 7 be in light contact with the belt, and means are provided for 20 adjusting the same to and from the belt as will presently appear. The axis of the cleaner member 7 is adapted to be arranged at an angle to the direction in which the belt is moving whereby matter accumulating 25 on the belt will engage the cleaner member causing the same to rotate to thereby remove the said matter laterally from the belt after the manner of a street sweeper. The brush or cleaner member 7 may be of any suitable 30 width, depending on the size of the zone on the belt it is desired to clean. As shown on the drawing the central portion only of the belt is cleaned, it being found in practice that this is sufficient to prevent slipping of 35 the belt.

40 The cleaner member 7 may be and preferably is adjustably mounted in the supports 8, these supports being provided with vertical slots 13 for this purpose. In order to limit the pivotal movement of the arms 9 and 10 the bracket 11 may be provided with stops 14 and 15 arranged above and below said arms.

45 In the operation of the device the bracket 11 is so mounted that the guides 12 will contact the pulley engaging face of the belt 2. The belt cleaning device 7 is then adjusted until the same is in close proximity to or lightly contacts the surface of said belt.

50 Upon the accumulation of sleet, snow or other foreign matter on the belt 2 the same will engage the cleaner member 7 causing the same to rotate and thereby remove said material laterally from the belt.

55 In the form of the device shown in Figs. 3 and 4 no guides are employed. The belt cleaner 7 is mounted in a bracket 15 which is hingedly connected to the support 16 as at 60 17. The bracket 15 is provided with an extension 18 on which is adjustably mounted a counterweight 19. The counterweight 19 may be adjusted along the extension 18 for balancing the weight of the bracket 15 to insure the proper contact of the cleaner member 7 with the belt 2. If desired, the

cleaner member 7 may be mounted in blocks 21 slidably mounted in vertical slots 22 in the bracket 15. Light springs 23 may be provided for holding the cleaner member in contact with the belt.

70 In the form of the device shown in Figs. 5 and 6 the cleaner member 7 is rotatably mounted on the arms 24 which engage opposite sides of the rigid support 25 and are pivotally connected thereto as by means of the bolt 26. The support 25 is provided at its free end with an arcuate slot 27 in which is adapted to engage a bolt 28 carried by the arms 24 for adjusting the brush to or from the belt 2. By means of this arrangement the cleaner 7 may be adjusted in proximity to the belt 2 or in contact therewith as may be desired.

75 If desired, the roller journal blocks 29 may be slidably mounted in slots 31 in the arms 24, and may be engaged by light springs 32 for holding the cleaner lightly against the belt, as in the form of the device shown in Figs. 3 and 4.

80 The cleaner or cleaner member 7 may be of any suitable construction, either rotating or otherwise. Preferably a rotating brush of wire or fiber is employed. One form of such brush is shown in Figs. 7 and 8 in which a plurality of disks 33 having a suitable number of mating grooves in which the wires or fibers 34 are adapted to be clamped, is provided. The disks 33 are mounted on a bearing sleeve or hub 35 and are clamped against the hub flange 36 by the flange member 37 threaded on the end of the hub 35. The hub 35 is rotatably mounted on the axle or pin 38 which may be journaled in the journal boxes 29 slidably mounted in the slots 31 in the arms 24, the same being forced 95 toward the outer ends of said slots by the springs 32, as shown in Figs. 6 to 8 inclusive.

100 In the form of the device shown in Figs. 9 and 10 the cleaner member 7 is composed of a series of thin disks 41 spaced apart by the 110 spacers 42 mounted on the bearing sleeve 43. A nut 44 is adapted to clamp the disks and spacers against the flange 45 on the end of the sleeve 43. The bearing sleeve 43 is adapted to be mounted on the spindle or 115 journal 38 as in the construction shown in Fig. 8.

120 The operation of the device shown in Figs. 9 and 10 is substantially the same as that described above, the movement of the belt causing the rotation of the disks which removes the foreign matter laterally from said belt.

125 It is thought from the foregoing taken in connection with the accompanying drawings that the construction and operation of my device will be apparent to those skilled in the art, and that various changes in size, shape, proportion and details of construction may be made without departing from 130

the spirit and scope of the appended claims.

I claim as my invention :—

1. The combination with a friction driving belt, of means associated with the inner 5 friction driving face thereof for scraping therefrom accumulations of foreign matter adhering thereto and including a freely rotatable roller mounted independently of the belt for yieldable scraping movements to- 10 wards and away from the belt, said roller having its periphery in frictional scraping engagement with the inner face of the belt for rotation thereby and its axis of rotation disposed oblique to the travel of the belt.

2. A driving belt cleaner for scraping ac- 15 cumulations from the inner friction driving face of a friction driving belt, comprising a supporting bracket for mounting the device in cooperative relation with a drive belt, and a freely rotatable scraping roller mounted 20 upon the bracket with its axis of rotation disposed so that the roller will lie oblique with respect to the travel of the belt when the periphery of the roller is in frictional scraping contact therewith and said roller 25 being mounted for yielding scraping movements towards and away from the belt.

ERNEST LUNN.
